R. F. GOOD,
ILLUMINATING DEVICE FOR REPRODUCING MACHINES,
APPLICATION FILED JUNE 24, 1921.

1,424,352.

Patented Aug. 1, 1922.

FIG. 1.

FIG. 2.

FIG. 3.

By his Attorneys

Edgar State & Co.

UNITED STATES PATENT OFFICE.

ROBERT F. GOOD, OF NEW YORK, N. Y.

ILLUMINATING DEVICE FOR REPRODUCING MACHINES.

1,424,352.

Specification of Letters Patent. Patented Aug. 1, 1922.

Application filed June 24, 1921. Serial No. 480,077.

To all whom it may concern:

Be it known that I, ROBERT F. GOOD, a citizen of the United States, and residing at New York, in the county of Bronx and State of New York, have invented certain new and useful Improvements in Illuminating Devices for Reproducing Machines, of which the following is a specification, such as will enable those skilled in the art to 10 which it appertains to make and use the same.

This invention relates to reproducing machines or talking machines of various kinds and classes, and particularly to devices for 15 illuminating the exposed operative parts of such machines, and the object of the invention is to provide a device of this class in the form of a figure supporting or holding a miniature record or a representation of the 20 same, and in connection with which an electric light bulb is mounted; a further object of the invention is to provide an illuminating device of the class specified in the form of a single unit which may be detachably 25 mounted in connection with the framework of the machine; and with these and other objects in view the invention consists in a device of the class and for the purpose specified which is simple in construction and operation and efficient in use, and which is 30 constructed as hereinafter described and claimed.

The invention is fully disclosed in the following specification, of which the accompanying drawing form a part, in which the 35 separate parts of my improvement are designated by suitable reference characters in each of the views, and in which:—

Fig. 1 is a sectional view of a part of a 40 reproducing machine showing my improved illuminating device mounted in connection therewith with part of said device in section;

Fig. 2 a sectional view of the device 45 shown in Fig. 1, with part of the construction omitted; and,

Fig. 3 a diagrammatic view showing the electric circuit of the device.

In Fig. 1 of the drawing I have shown 50 at 5 the top frame member of the cabinet of a reproducing machine of any kind or class which is usually provided at a predetermined point with a plurality of apertures 6 in which cups 7 are mounted, said 55 cups being adapted to receive the reproducing needles used in machines of this

class and, in the practice of my invention, one of these cups is preferably removed and my improved illuminating device 8 mounted in connection with the machine, or 60 the top member 5 thereof by passing said device downwardly through the aperture 6 from which the said cup is removed.

In the accompanying drawing my improved illuminating device 8 is shown for 65 the purpose of illustration to represent a statuette or figure 9 of "Miss Columbia," and this statuette is preferably made hollow in its construction and is provided with a base 10 having downwardly directed 70 internally threaded sleeve 11. The hands 12 of said figures are shown supporting or holding a disk 13 fashioned to represent a reproducible record such as employed in machines of the class specified, and the face 75 of this record may be provided with suitable advertising material as indicated at 14.

The figure 9, or the disk 13 thereof, is provided with an aperture 15 which opens inwardly and outwardly through said figure, and in which a threaded socket 16 is mounted, said socket being provided at its inner end with a transverse disk 17 composed of insulating material in the center of which is mounted a contact member 18 80 in connection with which a similar member 19 on the inner face of an electric-light bulb 20 is adapted to operate, as clearly shown in Fig. 3.

Connected with the contact member 18 is 90 a circuit wire 21 which passes downwardly through the figure 9 and is provided with a switch device 22 which is mounted upon the back of said figure, as shown in Fig. 2, and said wire is also connected with a contact member 23 mounted in a disk 24 composed of insulating material, which disk is mounted within the base 10 at the upper end portion of the sleeve 11 thereof as shown in Fig. 2. Another circuit wire 25 is connected with the socket member 16 and with a contact ring 26 imbedded in and exposed 95 downwardly through the disk 24, as clearly shown in Fig. 3.

A thimble-shaped member 27 is detachably mounted in connection with the downwardly directed sleeve 11 of the statuette or figure 9 and a suitable battery 28 is adapted to be mounted in said member and is provided centrally of the top face thereof with 105 a contact member 29 adapted to engage the contact member 23, and at one side of the

upper end portion of said battery is a spring contact piece 30 which is adapted to bear upon the contact ring 26. The contact member 29 and spring contact piece 30 are adapted to be held in firm engagement with the contact member 23 and ring 26 respectively by a spring 31 mounted in the thimble-shaped member 27 below the battery 28 therein.

10 It will be noted, in the form of construction shown, that the wires 21 and 25 pass upwardly through the separate legs of the figure, and it will also be apparent that the various parts of the device may be assembled and passed downwardly through the aperture 6 in the top member 5 of the cabinet of the machine, and rotatably adjustable to direct the rays of light from the bulb 20 in the proper direction, and in making up 15 the device the height thereof above the top 5 of the cabinet will be such as to permit of the closing of the cover usually employed in machines of this class.

20 The device is designed particularly for use in operating machines of the class specified in dark rooms, or where no other light is present, and the object is to direct a ray of light upon the exposed operative parts of the machine to permit of the proper setting of such parts in starting a machine or 25 in performing other operations.

It will be apparent that I am not necessarily limited to any particular form or design of figure or statuette employed, the 30 principal object being to provide a suitable ornamental and attractive figure supporting or holding a miniature record or representation of the same in which, or in connection with which the electric light bulb is 35 mounted, and the provision of a suitable source of electrical supply for such bulb, and while I have shown certain details of construction for carrying my invention into effect, it will be understood that I am not 40 necessarily limited to these details, and various changes therein and modifications thereof may be made, within the scope of the appended claims, without departing 45 from the spirit of my invention or sacrificing its advantages.

Having fully described my invention, what I claim as new and desire to secure by Letters Patent is:—

1. The combination with a sound reproducing machine of the class described, 55 of a suitable statuette, an electric light bulb socket mounted in said statuette, said statuette being provided with a base adapted to be passed downwardly through an aperture in the top board of the machine, means for supporting a battery in connection with said base, and means for placing said battery in electric circuit with 60 said socket.

2. The combination with a sound reproducing machine of the class described, 65 of a suitable statuette, an electric light bulb socket mounted in said statuette, said statuette being provided with a tubular base adapted to be passed downwardly through 70 an aperture in the top board of the machine, means for mounting a battery in connection with said base, and means for placing said battery in electrical communication with said socket, said means passing through the 75 statuette.

3. An illuminating device of the class described comprising a suitable statuette, a representation of a reproducible record supported thereby, and an electric light bulb 80 socket mounted centrally thereof, said representation of a record being adapted to throw the rays of light from the bulb upon the objects to be illuminated.

4. An illuminating device as claimed in 85 claim 3, in which the statuette is provided with a battery holder, said holder being adapted to be passed through an aperture in the top board of a reproducing machine to support said device in connection with the 90 machine.

In testimony that I claim the foregoing as my invention I have signed my name in presence of the subscribing witnesses this 23rd day of June 1921

ROBERT F. GOOD.
